UNITED STATES PATENT OFFICE

BERNARD A. STERLING, OF CHICAGO, ILLINOIS

HAIR WAVER

Application filed October 24, 1930. Serial No. 490,909.

My invention relates to hair wavers, and more particularly to an improved winding device for wrapping or curling the hair, and which may be used in connection with a heater for producing a permanent wave.

My invention provides a device which is not limited to winding the hair in one direction, but is adapted to wind same in either direction, i. e., right hand or left hand, selectively.

My invention provides improved means for locking the hair to the spindle means of the winding device.

My invention provides for combing the hair as the winding device is operated.

My invention provides for keeping the hair out of the way of operator's hand and for guiding the hair in an improved manner.

My invention provides an improved formation for pressing the hair as the winding device is operated.

My invention is illustrated in the accompanying drawing in which:

Figure 1 is a plan elevation of one embodiment of the invention;

Figure 2 is a cross section taken on the line 2—2 of Figure 1;

Figure 3 is a cross section taken on the line 3—3 of Figure 1;

Figure 4 is a perspective view of the winding part which turns about the spindle means of the device;

Figure 5 is an enlarged section taken longitudinally through the winding part on the line 5—5 of Figure 2 and with the spindle means in elevation;

Figure 6 is a cross section taken on the line 6—6 of Figure 1, showing the means for locking the hair to the spindle means and the formation of the spindle means; and

Figure 7 is a detail section taken on the line 7—7 of Figure 1, showing the means for locking the spindle sleeve and spindle rod against relative rotation.

The spindle means comprises a rod 10 and a surrounding sleeve 11. Rigidly fixed on one end of the rod 10 is a jaw member 12, and rigidly fixed upon the adjacent end of the sleeve 11 is a jaw member 13. The opposite

end of rod 10 has threaded engagement at 14 with a nut 15 adapted to be threaded along the rod into abutting engagement with the adjacent end of sleeve 11 at 16 to lock rod 10 and sleeve 11 against relative turning movement and thereby jaws 12, 13 closed upon the hair 17. Jaws 12, 13 are released so that they may be swung apart to open position or together to closed position by threading nut 15 out of shutting engagement with sleeve 11. Swinging of jaws 12, 13 is accomplished by relative turning movement between rod 10 and sleeve 11, which is conveniently imparted by loosening the nut 15 and imparting relative turning movement.

The winding part 19 has a generally cylindrical portion 20 surrounding and rotatably mounting said part upon the spindle sleeve 11. This part 19 may be of sheet metal, and its forward end is notched at 21 and provided with two integral wings flaring upwardly from the opposite sides of notch 21. Along notch 21 cylindrical portion 20 is provided with an enlargement 22' adapted to receive the hair passing through notch 21 and between the spindle means and the generally cylindrical portion of the winding part, and this enlargement is preferably cylindrical to avoid steps in the curl or wave produced.

Spaced below or longitudinally away from the wings 22 in a direction away from the locking jaws 12, 13, the winding part 19 has a second pair of integral wings 24 flared upwardly and between which the strands of hair 17 are guided longitudinally of the spindle means between the wings 22 and from the notch 21. A cover 25 hinged along one longitudinal side at 26 to the adjacent longitudinal edge of one of the wings 24 is provided along its opposite longitudinal edge with a catch 27 adapted to be sprung into latching engagement with a flange or cooperating catch 28 along the longitudinal edge of the other wing 24 whereby the cover 25 is latched closed, confining the strands of hair being operated upon between the guide wings 24 and keeping the hair out of the way of the operator's hand and against extending out laterally from the winding part.

At one end, preferably the forward end, as

shown, the cover 25 has an integral flange 29 turned inwardly toward the spindle part and serrated at 30 to form a comb which engages and combs the hair as it is guided through the guide formed by the wings 24 and the cooperating cover 25.

The top of the cylindrical portion 20 of the winding part 19 may completely encircle the spindle sleeve 11 between the guide wings 24 and the wings 22, as shown at 32, and the projecting end 33 of the cylindrical portion 20 may substantially completely encircle the spindle sleeve, as shown, it being understood that when the winding part is of sheet metal these portions 32 and 33 may be split longitudinally so that the entire body of the winding part may be stamped from a single flat piece of sheet metal and then formed to shape.

In operation the strands of hair 17 are gripped and locked between the jaws 12, 13 at the usual or any desired place along the hair, and the strands are then laid longitudinally of the spindle means between the wings 22 and between the guide wings 24, the cover 25 being opened for this purpose, whereupon the cover 25 is closed to confine the hair between the guide wings. Then by turning the winding part either clockwise or counter-clockwise about the spindle sleeve 11, the strands of hair are curled or wrapped through the notch 21 and upon the spindle sleeve 11 between this sleeve and the enlarged cylindrical portion 20 of the winding part 19. The strands of hair are preferably curled upon the spindle in overlapping relation, which overlapping relation is obtained by the helical wrapping of the hair strands produced by the turning of the winding part 19 around the spindle sleeve 11 and the movement of the winding part 19 longitudinally along the spindle in a direction away from the locking jaws 12, 13, which results from the wrapping of the hair upon the spindle ahead of the winding part, and the longitudinal movement of the winding part which is produced by this wrapping of the strands of hair ahead of it, it being understood that the winding part has free turning and longitudinal movement upon the spindle sleeve 11.

The cylindrical formation of the enlarged portion 22 of the winding part 19 imparts a generally cylindrical contour to the curl or wave produced and avoids flaring of the successive convolutions of the curl and the steps which are produced in such a curl where such flaring occurs.

The enlarged cylindrical portion 22 may be provided with an internal longitudinal hump or ridge 40 conveniently formed by a longitudinal depression in the wall of the cylindrical portion 22. This internal ridge or hump presses the hair as it is curled upon the spindle and further enhances the smooth, even finish imparted to the curl.

I do not intend to be limited to the precise details shown or described.

I claim:

1. In a device of the class described, a spindle, a hair locking jaw rigid with one end of said spindle, a spindle sleeve surrounding said spindle, a cooperating hair locking jaw rigid with the end of said sleeve adjacent said first jaw, said sleeve extending substantially to the opposite end of the spindle and 75 said jaws being opened and closed by relative rotation between said spindle and said sleeve.

2. In a device of the class described, a spindle, a hair locking jaw rigid with one end of 80 said spindle, a spindle sleeve surrounding said spindle, a cooperating hair locking jaw rigid with the end of said sleeve adjacent said first jaw, said sleeve extending substantially to the opposite end of the spindle and 85 said jaws being opened and closed by relative rotation between said spindle and said sleeve, and means for locking said spindle and sleeve against relative rotation for locking said jaws closed.

3. In a device of the class described, a spindle, a hair locking jaw rigid with one end of said spindle, a spindle sleeve surrounding said spindle, a cooperating hair locking jaw rigid with the end of said sleeve adjacent said 95 first jaw, said sleeve extending substantially to the opposite end of the spindle and said jaws being opened and closed by relative rotation between said spindle and said sleeve, means for locking said spindle and sleeve against relative rotation for locking said 100 jaws closed, said means comprising a member having threaded engagement with the spindle and adapted to be threaded into and out of abutting engagement with said sleeve.

4. In a device of the class described, a spindle member, means for securing a lock of hair to said spindle member, a winding part rotatable about and longitudinally movable upon said spindle member, said winding part 110 having one end disposed toward the securing means and provided with a notch formed to permit wrapping a strand of hair helically around said spindle member by rotation of said winding member thereon, guide wings 115 for the hair one along each of the opposite sides of said notch, and means at the opposite end of said winding part for guiding the lock of hair longitudinally along the spindle.

5. In a device of the class described, a spindle member, a winding part rotatable about and longitudinally movable upon said spindle member, said winding part having a notch formed to permit wrapping a strand of hair helically around said spindle member by 125 rotation of the winding part thereon, and means for guiding the strands of hair longitudinally and for holding same out of the way of the operator's hand and against extending laterally from said slot, said means 130

comprising a pair of wings on the winding part and a cover coacting with said wings.

6. In a device of the class described, a spindle member, a winding part rotatable about and longitudinally movable upon said spindle member, said winding part having a notch formed to permit wrapping a strand of hair helically around said spindle member by rotation of the winding part thereon, and means for guiding the strands of hair longitudinally and for holding same out of the way of the operator's hand and against extending laterally from said slot, said means comprising a pair of wings on the winding part and a cover coacting with said wings, said wings flaring outwardly and the cover being hinged to one of said wings and provided with a latch having latching cooperation with the other wing.

7. In a device of the class described, a spindle member, a winding part rotatable about and longitudinally movable upon said spindle member, said winding part having a notch formed to permit wrapping a strand of hair helically around said spindle member by rotation of the winding part thereon, means for guiding the strands of hair longitudinally and for holding same out of the way of the operator's hand and against extending laterally from said slot, said means comprising a pair of wings on the winding part, a cover coacting with said wings, and a comb on said cover.

8. In a device of the class described, a spindle member, a winding part rotatable about and longitudinally movable upon said spindle member, said winding part having a notch formed to permit wrapping a strand of hair helically around the spindle member by rotation of the winding part thereon, means for guiding the strands of hair longitudinally and for holding same out of the way of the operator's hand and against extending laterally from said slot, and a comb associated with said last means for combing the hair in the operation of the device.

9. In a device of the class described, a spindle member, a winding part rotatable about and longitudinally movable upon said spindle member, said winding part having a notch formed to permit wrapping a strand of hair helically around said spindle member by rotation of the winding part thereon and an enlarged substantially cylindrical portion adjacent said notch and spaced from the spindle to receive the strand of hair between it and the spindle.

10. In a device of the class described, a spindle member, a winding part rotatable about and longitudinally movable upon said spindle member, said winding part having a notch formed to permit wrapping a strand of hair helically around said spindle member by rotation of said winding part thereon and an internal hump in said winding part for

pressing the hair in the operation of the device.

11. In combination, a mandrel, a revolvable winder for wrapping hair around said mandrel, means for causing the unwound portion of the hair to lie longitudinally along the mandrel, and a comb on said winder.

12. In a device of the class described, a spindle member having means for securing a lock of hair at one end thereof, a winding member rotatable about and longitudinally slideable upon said spindle member, said winding member having a notch formed therein for wrapping a strand of hair evenly about said spindle in either direction of rotation, means for causing the unwound portion of the strand of hair to lie longitudinally along the spindle, said hair being drawn from said last named means during the winding operation, and a pair of integral wing members for guiding the withdrawal of said hair from said means when said winding member is rotated.

13. In combination, a mandrel, a revolvable winder for wrapping hair about said mandrel, means for causing the unwound portion of said hair to lie longitudinally along the spindle, and a hinged member including a comb and carried by said last named means for engaging the unwound portion of said hair as the winder is being revolved.

14. In combination, a mandrel, a revolvable winder for wrapping hair around said mandrel, means for causing the unwound portion of said hair to lie longitudinally along said mandrel, a comb hingedly mounted on said last named means for engaging the unwound portion of said hair as it is withdrawn during the winding operation, and a pair of wing members integral with said winder for guiding the withdrawal of said hair when said winder is revolved.

15. A winding member of the class described comprising a hair receiving notch portion, a collar including diverging guide wings and a humped portion for guiding and pressing said hair during the winding operation, a hinged cover member disposed over said notched portion, and a comb carried by said cover member and disposed normal to the axis of rotation of said winding member.

In witness whereof, I hereunto subscribe my name this 27th day of September, 1930.
